UNITED STATES PATENT OFFICE.

ALBERT LATHAM, OF BEVERLY, MASSACHUSETTS, ASSIGNOR TO UNITED SHOE MACHINERY COMPANY, OF PATERSON, NEW JERSEY, A CORPORATION OF NEW JERSEY.

SKIVING-KNIFE.

1,232,428.

Specification of Letters Patent.

Patented July 3, 1917.

Application filed May 19, 1916. Serial No. 98,614.

To all whom it may concern:

Be it known that I, ALBERT LATHAM, a citizen of the United States, residing at Beverly, in the county of Essex and State 5 of Massachusetts, have invented certain new and useful Improvements in Skiving-Knives; and I do hereby declare the following to be a full, clear, and exact description of the invention such as will enable 10 others skilled in the art to which it appertains to make and use the same.

The present invention relates to skiving knives, and more particularly to skiving knives of the type in which a thin knife 15 blade is clamped to a tubular knife holder.

The object of the present invention is to provide a skiving knife of an improved type in which the knife blade may be conveniently adjusted with relation to the holder 20 and is firmly clamped to the holder by a simple and efficient mechanism.

With this object in view, a feature of the invention contemplates the provision, in a knife of this type having a knife holder and 25 a knife blade, of mechanism for clamping the blade to the holder, comprising a clamping ring, a centrally disposed actuating member movable axially to operate the clamping ring, and connections between the 30 actuating member and clamping ring for causing the clamping ring to engage with the blade throughout the entire peripheral surface.

Still further features of the invention consist in certain novel features of construction, 35 combinations and arrangements of parts thereinafter described and claimed, the advantages of which will be obvious to those skilled in the art from the following description.

In the accompanying drawings illustrating the preferred form of the invention, Fig. 1 represents a section in elevation of the 45 skiving knife taken upon the line 2—2 of Fig. 2; and Fig. 2 represents a front elevation, partly in section, of the skiving knife taken on the line 1—1, of Fig. 1.

In the present invention, the knife blade is conveniently clamped to the holder 50 through the provision of a single actuating member which is manipulated by the operator to expand the clamping ring. Upon releasing the knife blade it may be adjusted with relation to the holder in the usual 55 manner. In the illustrated embodiment of

the invention, the clamping ring is operated to engage with the knife blade through a series of radially disposed pins which operatively engage at their inner ends with the actuating member, and at their outer ends 60 with an operating ring, which is adapted to engage with and move the clamping member. The opposite ends of the pins and coöperating faces of the actuating member and operating ring are inclined to cause an axial 65 movement of the actuating member to impart radial outward movements to the pins and a corresponding axial movement in an opposite direction to the operating ring. The clamping ring is engaged in proximity 70 to its outer periphery by a fixed head, which forms a fulcrum about which the ring is rocked by the pressure of the operating ring against the inner edge. The skiving knife comprises a substantially cylindrical knife 75 holder 5 which is supported by a head 6, mounted upon the usual knife shaft 7. A knife blade 9 is supported within the holder upon a carrier 10, which is threadedly mounted upon a hub 12, secured to the head 80 6 through a plurality of clamping bolts 14. The knife holder 5 is locked against rotation relative to the carrier 10 by a series of studs 15 threadedly secured in the holder and received in apertures formed in the 85 carrier and of sufficient length to form guiding members for the carrier during the relative movements of the carrier and knife holder. The knife blade is secured to the carrier adjacent its inner edge in the usual 90 manner, and is conveniently adjusted relative to the holder by relatively rotating the holder 5 and knife shaft 7. It will be observed that in the present construction the holder is journaled upon the hub 12, and by 95 retaining the holder stationary and rotating the knife shaft, the hub 12 will be rotated to move the carrier 10 in an axial direction.

The knife blade is conveniently clamped to the holder by an internal clamping member which is operated by a single centrally disposed actuating member arranged conveniently to the operator. To this end, an annular clamping ring 20 is arranged with its outer periphery supported in proximity 100 to the inner surface of the knife blade, and is engaged adjacent its inner edge by an operating ring 22, slidably supported in the hub 12. The operating ring is moved axially and serves to rock the clamping ring 110

about the edge of a cup-shaped head 23 having a hub 24 on which the clamping ring 20 is loosely supported. The operating ring 22 is moved axially to press the clamping ring against the knife blade by a series of sliding pins 26 supported radially in recesses formed in the hub 12, and arranged to engage with the operating ring at a plurality of points equidistant from one another. The pins 26 are operatively connected at their inner ends with an actuating member 28, supported concentrically with relation to the pins. The inner face 29 of the actuating member and the inner ends of the pins co-operating therewith are tapered, as shown clearly in Fig. 1, and the outer ends of the pins and co-operating face of the ring 22 are tapered in the opposite direction to cause an axial movement of the member 28 to impart a like movement in the opposite direction to the ring 22. The head 23 is clamped in position upon the hub 12 by a retaining member 30, threadedly secured in the hub and having a flange 31 which engages with a corresponding annular recess formed in the hub 24 to clamp the two members 12 and 24 together. The actuating member 28 is conveniently received in an internally threaded bore formed in the member 30, and is provided with a transverse slot 32 for the reception of an operating tool. With this construction, upon rotating the actuating member to move the member inwardly, the pins 26 are moved outwardly in radial directions, causing an axial movement of the ring 22 into engagement with the inner edge of the clamping ring 20. The pressure thus exerted against the inner edge of the clamping ring causes the ring to fulcrum about the periphery of the head 23 and firmly clamp the knife blade to the holder throughout all portions of the periphery. In order to facilitate the clamping action of the ring 20, it is conveniently provided with a series of radially disposed slots 34, as shown clearly in Fig. 2.

It will be obvious that the clamping ring will tend to exert a relative rotation of the knife holder and knife shaft. In order to effectually prevent a rotation of the two members after the knife blade has been adjusted and clamped in position, however, mechanism is provided for firmly clamping the knife holder to the hub 12. To this end, a ring 35 is supported in the hub 12 and is provided with a series of studs 37, the ends of which engage with the inner face of the holder 5. In order to cause the studs to engage with and clamp the knife holder when the clamping ring 20 is actuated, the inner face of the ring 35 is slightly tapered and is adapted to be engaged by a correspondingly tapered face 38 formed upon each of the sliding pins 26, opposite the tapered face of the pin which engages with

the ring 22. With this construction, when the pins are moved outwardly they serve to actuate both of the rings 22 and 35 in opposite directions. In order to permit the pins to properly actuate both of the rings, each pin is loosely supported in the corresponding radial slot formed in the hub 12 and has provision for a slight lateral movement. With this construction the pins, moving outwardly, first cause the ring 35 to assume a clamping position and thereafter the faces of the pins engaging with the ring may be moved laterally in addition to the radial movement to operate the clamping ring 20.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

1. A skinning knife, having, in combination, 90 a knife holder, a knife blade, a clamping ring adapted to clamp the blade to the holder, a centrally disposed actuating member movable axially to operate the clamping ring, and operative connections between the 95 actuating member and clamping ring, including a plurality of radially disposed pins.

2. A skinning knife, having, in combination, 100 a knife holder, a knife blade, a clamping ring supported within the knife blade, an actuating member, and a series of radially disposed pins operatively connected at opposite ends with the actuating member and the clamping ring and arranged to operate the 105 clamping ring upon an axial movement of the actuating member.

3. A skinning knife, having, in combination, 110 a knife holder, a knife blade, a clamping ring supported within the blade, an operating ring engaging with the clamping ring adjacent its inner edge, a centrally disposed actuating member, and operative connections between the actuating member and operating ring for moving the operating 115 ring axially upon an axial movement of the actuating member.

4. A skinning knife, having, in combination, 120 a knife holder, a knife blade, a clamping ring supported within the blade, a retaining head engaging at its outer edge with the clamping ring, and an actuating member operatively connected with the clamping ring to rock the clamping ring about the edge of the retaining head.

5. A skinning knife, having, in combination, 125 a hub, a knife holder supported upon the hub, a knife blade supported within the holder, a clamping ring, a series of pins positioned radially in the hub and having 130

inclined inner ends, an actuating member having an inclined face engaging with the inner ends of the pins, and operative connections between the outer ends of the pins 5 and the clamping ring.

6. A skiving knife, having, in combination, a hub, a knife holder supported upon the hub, a knife blade, a clamping ring, means for clamping the knife holder to the 10 hub, and a single actuating member arranged to operate the clamping ring and the means for clamping the knife holder.

7. A skiving knife, having, in combination, a hub, a knife holder supported upon 15 the hub, a knife blade, and mechanism comprising a single actuating member for clamping the knife holder to the hub and for clamping the blade to the holder.

8. A skiving knife, having, in combination, a hub, a knife holder supported upon the hub, a knife blade, a clamping ring for the knife blade, an operating ring supported in the hub, a knife holder clamping ring, a 20 series of radially disposed pins engaging 25 with the operating ring and knife holder clamping ring, and means for actuating the pins to operate both of the rings to clamp the knife blade to the holder and the knife holder to the hub.

30 9. A skiving knife, having, in combination, a knife holder, a knife blade, a clamping ring, an operating ring engaging with the clamping ring adjacent its inner edge

and having an inclined face, a series of radially disposed pins having inclined outer 35 ends engaging with the inclined face of the operating ring and inner ends inclined in the opposite direction, and an actuating member having an inclined face engaging with the inner ends of the pins.

40 10. A skiving knife, having, in combination, a knife holder, a knife blade, a clamping ring, a retaining head for the ring, a centrally disposed member for retaining the head in position having an internally 45 threaded bore, an actuating member threaded in the bore, and operative connections between the actuating member and clamping ring.

50 11. A skiving knife, having, in combination, a knife holder, a knife blade, a clamping ring, a series of radially disposed pins, a pair of oppositely disposed rings engaging with the outer ends of the pins, and means for moving the pins to separate the 55 rings.

60 12. A skiving knife, having, in combination, a hub, a knife holder supported upon the hub, a knife blade, a clamping ring, a series of pins sliding in a lengthwise direction in the hub and having provision for lateral movement, a pair of rings supported in the hub and engaging with opposite sides of the pins, and means for actuating the pins to separate the rings.

ALBERT LATHAM.
